TERTIARY AMYL ORTHO-CRESOL

George W. Raiziss and Le Roy W. Clemence,
Philadelphia, Pa., assignors to Abbott Laboratories,
North Chicago, Ill., a corporation of Illinois

No Drawing. Original application June 22, 1934,
Serial No. 731,898. Divided and this applica-
tion February 17, 1937, Serial No. 126,200

1 Claim. (Cl. 260—624)

The present application is a division of our application filed June 22, 1934, Serial No. 731,898 for Alkyl cresols.

Our invention relates to a group of compounds which have bactericidal and bacteriostatic value, and may be classed broadly as alkyl cresols and more particularly as tertiary-amyl cresols. They are also of value as intermediates for halogenated alkyl cresols which also have bactericidal and bacteriostatic value and which are described and claimed in certain of our co-pending applications.

It is known that the germicidal value of chemical compounds is generally greatly reduced in the presence of blood serum or whole blood. The compounds which we have discovered and which form the subject matter of this application are of high germicidal value in the presence of blood serum and at the same time are of low toxicity, so that our new compounds can be introduced into the human body in relatively high concentrations without any deleterious effect to the patient.

Our new compounds which are specifically described herein, comprise the substantially pure tertiary-amyl derivatives of ortho, meta, and para cresols. All of these compounds may be made by substantially the same process, which is essentially as follows.

204 grams of zinc chloride is dissolved with heating and mixing in 132 grams of tertiary-amyl alcohol. The temperature is raised to the appropriate reaction temperature set forth below; in the case of tertiary-amyl-ortho-cresol this would be 140° C. 108 grams of the desired cresol, ortho-cresol in this case, is then added gradually. After the addition is complete the temperature is maintained until the mixture separates into two layers and is then continued for about one hour until a maximum separation occurs. The mixture is then cooled and poured into two liters of water containing a small amount of HCl. The oily layer which separates is then washed with water several times, and is extracted with three portions of 10 percent NaOH (about 300 cc. in each portion). The alkaline extract is allowed to stand until there is a clear separation of the insoluble oil. This is removed by extraction with petroleum ether until the alkaline layer no longer becomes cloudy on diluting a small sample with water. The alkaline portion is drawn off and then acidified with HCl. The oil which is liberated is separated, washed with water and then distilled in

vacuo. The desired fraction is collected at the boiling points set forth below; in the case of tertiary amyl-ortho-cresol, the desired product would be collected at 135°—137° C. at 10 mm. pressure. The product has a specific gravity of 0.973.

The various other products are obtained by the same procedure, substituting the appropriate cresol according to the product desired.

All of the compounds disclosed herein are substantially colorless oils, soluble in organic solvents, completely soluble in dilute alkalies, and insoluble in water.

The physical properties of the compounds which we have prepared are as follows:

No.	Compound	B. P. °C.	Press. Mm.	Sp. gr.	Max. react. temp.
1...	Tertiary-amyl-ortho-cresol...	135-137	10	0.973	140
2...	Tertiary-amyl-meta-cresol...	137-140	11	0.973	140
3...	Tertiary-amyl-para-cresol...	134-141	10	0.992	135

The above compounds may have the following graphic formulae:

Tertiary-amyl-ortho-cresol

Tertiary-amyl-meta-cresol

Tertiary-amyl-para-cresol

We claim:

A germicidal agent having high germicidal value combined with low toxicity in the presence of blood serum consisting of substantially pure tertiary-amyl-ortho-cresol, said agent having a boiling point of about 135°—137° C. at 10 mm. pressure and being completely soluble in dilute alkali.

GEORGE W. RAIZISS
LE ROY W. CLEMENCE.
